MARINE LOG.

1,307,624.

Specification of Letters Patent. Patented June 24, 1919.

Application filed January 6, 1919. Serial No. 269,755.

To all whom it may concern:

Be it known that I, EDGAR WALL DOREY, a subject of the King of Great Britain, residing at London, England, have invented 5 certain new and useful Improvements in Marine Logs, of which the following is a specification.

This invention relates to those devices, generally known as marine logs, which are designed to indicate the speed of travel of vessels at sea and the distance covered in any given time.

In devices of this kind a rotating member is trailed in the sea by means of a line or 15 rope connected to an indicating device, the said rotator being so formed that it is caused to rotate at a speed proportional to the speed of travel of the vessel.

In marine logs as heretofore constructed 20 the line is secured to the rotator in such a manner that the line is necessarily rotated by the rotator both when it is normally operating and also when it is being hauled in for inspection or for any other purpose. It has 25 been found that with this construction when it is desired to haul in the rotator the line must be hauled in twice in order to free the line from the kinks produced by its continued rotation while being hauled in.

The object of the present invention is to 30 provide a construction of marine log designed so as to avoid the above disadvantages. The improved marine log according to this invention is so constructed that the 35 line or rope is normally in engagement with and rotates with the rotator, but the construction is such that the line can be readily disengaged from the rotator and comprises a device for effecting the disengagement at 40 will, for instance when hauling the rotator in, thus enabling the rotator to rotate independently of the line.

In the accompanying drawings:

Figure 1 is a longitudinal sectional view 45 of a portion of the rotatable element of a marine log embodying the invention;

Fig. 2 is a view in sectional elevation showing a suitable form of a releasing device in position on the towing line;

Fig. 3 is a view in side elevation of the closing cap of the rotatable element shown in Fig. 1; and

Figs. 4 and 5 are detail views in side elevation of portions of the mechanism shown in Fig. 1.

55

Referring now to the drawings, the rotatable element of the log is shown as comprising a body portion 1 having the usual blades or vanes 2 and connected to the indicating device carried by the vessel by means 60 of a rope or line 3.

The forward end of the body portion 1 of the rotatable element is constituted by a cup-shaped member 4 secured to the body portion 1 and a closing 65 cap 5 provided with a screw-threaded portion 6 co-operating with a corresponding screw-threaded portion 7 formed on the cup-shaped member.

The closing cap 5 is so formed as to provide a minimum of resistance to the passage of the rotatable element through the water.

The connection between the towing line 3 and the rotatable element 1 of the log is effected as follows:

75

A hollow sleeve 8 having an enlarged portion or head 9 is provided, the portion 8 projecting through an opening 10 formed in the base of the cup-shaped member 4, the enlarged portion or head 9 engaging 80 with the base of the cup-shaped member 4 and constituting an abutment for the end of the towing line 3, which is secured to the sleeve 8 or the enlarged portion 9 either by means of the usual knot employed for securing the rotatable member to the line, or by other securing means. The inner end of the hollow sleeve 8 is cut away as indicated at 11 in Fig. 4 to form a sector-shaped projection or extension 12 for a purpose which 85 will be hereinafter explained.

Located in an opening formed in the interior of the closing cap 5 and surrounding the towing line 3 is a sleeve 13 having an enlarged sector-shaped projection or head 14 95 located within the interior of the cup-shaped member 4, the sleeve 13 being cut away as indicated at 15 in Fig. 5 and the extension or projection 14 being adapted in the position shown, to engage with the projection 100 12 on the sleeve 8 in such manner that the rotary movement of the sleeve 13 is transmitted to the sleeve 8.

The sector-shaped projection 14 of the

sleeve 13 is adapted to bear against the inner face 17 of the closing cap 5 in which position a portion 18 of the sleeve projects beyond the end of the closing cap 5.

5 The rotary movement of the sleeve 13 relatively to the closing cap 5 is in the position of the parts shown in Fig. 1 limited by a stop or projection 19 (see Fig. 3) the longitudinal displacement of the sleeve 13 being 10 adapted to free the sleeve from engagement with the stop 19. A spring 20 which may be one of a number of similar springs, is adapted to bear against the lateral face of the projection 14 of the sleeve 13 and to 15 maintain the same in the position shown.

Referring now particularly to Fig. 2, a flat plate or disk 21 is shown mounted upon a sleeve 22, the latter being so formed as to surround the towing line 3 and to maintain 20 the disk 21 substantially at right angles to the axis of the towing line when the releasing device is in position on the line.

The operation of this form of the invention is as follows:

25 In normal operation the rotatable element is towed by the vessel in the usual way, the number of revolutions on the part of the rotatable element being transmitted by means of the line to the indicating device carried 30 by the vessel, the rotary movement being transmitted from the body portion 1, the cup-shaped member 4 and the closing cap 5, which as before explained are rigidly connected together, to the sleeve 13 through the 35 projection 19 formed on the closing cap 5, to the sleeve 8 which is connected to the towing line, and to the indicating device on the vessel. The rotary movement of the sleeve 13 is transmitted to the sleeve 8 by reason 40 of the coöperation of the sector-shaped projections 12 and 16 formed on the sleeves 8 and 13 respectively.

When it is desired to haul in the log either 45 for inspection or other purposes the releasing device constituted by the disk 21 and sleeve 22 is permitted to travel down the line 3, along which it is carried by the action of the vessel traveling through the water as will be readily understood. The releasing device 50 may be normally carried on the line adjacent to the indicating device or may be placed on the line only when it is desired to effect the release of the parts. The releasing device will consequently be brought into engagement 55 with the extension 18 of the sleeve 13 which as already explained, projects somewhat beyond the closing cap 5, forcing the sleeve into the interior of the cup-shaped member 4, thereby removing the sector-shaped head or projection 14 from engagement 60 with the stop 19 formed on the inner wall of the closing cap 5.

It should be noted that the spring 20 bearing against the inner face of the enlarged portion 14 of the sleeve 13 must first

be moved to a position to permit of such longitudinal displacement on the part of the sleeve 13 but the spring 20 and such additional springs as may be provided are only of such strength as to maintain the sleeve 13 70 in the position shown against the action of the water acting upon the outer extremity 18 of the sleeve so that a sharp blow such as would be imparted to it by contact with the releasing device will be sufficient to effect 75 the release of this spring or springs and the consequent longitudinal displacement of the sleeve 13 in the manner described.

When the stop or projection 19 is not in engagement with the enlarged sector-shaped 80 portion or head 14 of the sleeve 13 the line is no longer rotated by the rotation of the rotatable element of the log and there is no tendency for the line to become kinked during the hauling-in operation, the rotatable 85 element being free to rotate upon the sleeves 8 and 13.

From the above description it will be apparent that simple and effective means are provided for releasing the rotatable element 90 of the log from the towing line so far as regards the rotary movement of the rotatable element being transmitted to the line, thus avoiding the disadvantage associated with logs of this description in the past whereby 95 it has been necessary, before the line could be coiled away, to first clear the line of kinks imparted to it by the rotation of the rotatable element of the log during the hauling-in operation; moreover damage to the line in 100 such circumstances is avoided.

The invention has been described as embodied in a standard form of rotatable element, the body portion of the rotatable element constituting the housing for the 105 releasing device.

It will be understood however, that the invention is not limited to the employment of any particular form of mechanism for preventing the rotary movement of the rotatable element being transmitted to the line nor to the employment of any particular construction of releasing device and modifications in these and other respects may be made within wide limits without exceeding 110 the scope of the invention.

I claim:

1. A marine log comprising a rotatable element, a registering device, a flexible connection for transmitting rotary movement 120 between said rotatable element and said registering device, and means for preventing the rotary movement of the rotatable element being transmitted to the registering device at any desired time.

2. In a marine log, the combination of a rotatable element, a registering device, a flexible connection between said rotatable element and said registering device, and means for disconnecting the rotatable ele- 130

ment from the flexible member at any time during operation.

3. In a marine log the combination of a rotatable element, a registering device, a flexible connection between said registering device and said rotatable element, clutch mechanism interposed between the end of the flexible connection and said rotatable element, and means for effecting the disconnection of the clutch mechanism at any time during operation.

4. In a marine log, the combination of a rotatable element, adapted to be towed by the vessel, a registering device, a flexible connection between said rotatable element and said registering device, clutch mechanism interposed between the end of the flexible connection and the rotatable element, and means for preventing the rotary movement of the rotatable element being transmitted to the registering device through the flexible connection at any desired time.

5. In a marine log, the combination of a rotatable element adapted to be towed by the vessel, a registering device, a flexible connection between said rotatable element and the registering device, clutch mechanism interposed between the end of the flexible connection and the rotatable element, and means dependent for its operation upon the passage of the ship through the water for effecting the operation of the clutch mechanism.

6. In a marine log, the combination of a rotatable element adapted to be towed by the vessel, a registering device located on the vessel, a flexible connection interposed between the rotatable element and the registering device, clutch mechanism located in the rotatable element, and means for preventing the rotary movement of the rotatable element being transmitted to the registering device at any desired time.

7. In a marine log, the combination of a rotatable element adapted to be towed by the vessel, a registering device located on the vessel, a flexible connection between said rotatable element and the registering device, clutch mechanism interposed between the end of the flexible connection and the rotatable element, and means for effecting the operation of the clutch mechanism from a point adjacent to the registering device.

8. In a marine log, the combination of a rotatable element adapted to be towed by the vessel, a registering device, a flexible connection between said rotatable element and said registering device, clutch mechanism interposed between the end of the flexible connection and the rotatable element, and a device adapted to travel along the flexible connection for effecting the operation of the clutch mechanism.

9. In a marine log, the combination of a rotatable element adapted to be towed by the vessel, a registering device, means for trans-

mitting the rotary movement of the rotatable element to the registering device and means for preventing the transmission of said rotary movement at any time during operation.

10. In a marine log, the combination of a rotatable element, a registering device operating in conjunction therewith, a flexible connection between said rotatable element and said registering device, clutch mechanism located in said rotatable element for transmitting the rotary movement of the rotatable element to the flexible connection, and a device adapted to travel along the flexible connection for effecting the disengagement of the clutch mechanism.

11. In a marine log, the combination of a rotatable element, a registering device operating in conjunction therewith, a flexible connection between said rotatable element and the registering device, clutch mechanism located in the rotatable element, a projection on said rotatable element for effecting the operation of the clutch mechanism, and a device adapted to coöperate with said projection for effecting the disengagement of the clutch mechanism.

12. In a marine log, the combination of a rotatable element adapted to be towed by the vessel, a registering device, a flexible connection between said registering device and said rotatable element, means for insuring the transmission of the rotary movement of the rotatable element to the flexible connection, and a device dependent for its operation on the passage of the ship through the water, for preventing the rotary movement of the rotatable element being transmitted to the registering device at any desired time.

13. In a marine log, the combination of a rotatable element, a registering device operating in conjunction therewith, a flexible connection between said rotatable element and said registering device, clutch mechanism between the flexible connection and the rotatable element for transmitting the rotary movement of the rotatable element to the flexible connection, and a device adapted to travel along the flexible connection for effecting the disengagement of the clutch mechanism.

14. In a marine log, the combination of a rotatable element adapted to be towed by the vessel, a registering device, a flexible connection between said rotatable element and the registering device, clutch mechanism interposed between the flexible connection and the rotatable element and a disk-shaped member adapted to travel along the flexible connection for disengaging said clutch mechanism.

15. In a marine log, the combination of a rotatable element adapted to be towed by the vessel, a registering device, a flexible con-

nection between said rotatable element and the registering device, clutch mechanism interposed between the flexible connection and the rotatable element and a disk-shaped member adapted to travel along the flexible connection under the action of the passage of the vessel through the water for disengaging said clutch mechanism.

In witness whereof I have hereunto set my hand in presence of two subscribing witnesses.

EDGAR WALL DOREY.
